(57) **CLAIM**

We claim the ornamental design for a display screen or portion thereof with transitional graphical user interface, as shown and described.

DESCRIPTION

FIG. 1 is the first image in a sequence for a display screen or portion thereof with transitional graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the eighth image thereof;

FIG. 9 is the ninth image thereof;

FIG. 10 is an enlarged view of the icon in FIG. 1, shown separately for clarity of illustration;

FIG. 11 is an enlarged view of the icon in FIG. 2, shown separately for clarity of illustration;

FIG. 12 is an enlarged view of the icon in FIG. 3, shown separately for clarity of illustration;

FIG. 13 is an enlarged view of the icon in FIG. 4, shown separately for clarity of illustration;

FIG. 14 is an enlarged view of the icon in FIG. 5, shown separately for clarity of illustration;

FIG. 15 is an enlarged view of the icon in FIG. 6, shown separately for clarity of illustration;
